UNITED STATES PATENT OFFICE

LELAND S. HAMER, OF LONG BEACH, CALIFORNIA, ASSIGNOR, BY DIRECT AND MESNE ASSIGNMENTS, TO JOHN GRANT, OF LOS ANGELES, CALIFORNIA

WELL REAMING TOOL

Application filed February 8, 1927. Serial No. 166,642.

This invention has to do with a reamer to be used in the drilling of wells, for instance, oil wells, and it is an object of the invention to provide a simple, effective and improved reamer for use with the rotary method of drilling.

There are certain characteristic difficulties inherent in practically all tools that have heretofore been provided for under-reaming wells. The cutting members are normally urged outwardly, are held in by the casing during the passage of the tool downwardly through the casing, and expand immediately upon the tool passing beyond the end of the casing. This makes it necessary for the operator to start the reaming operation immediately beyond the end of the casing. In other cases, the cutters are urged outwardly by springs or are designed to feed themselves outwardly, and in practice, open or feed outwardly so quickly that they imbed themselves in the formation, making it impossible to further operate the tool. In other cases, the cutters, after being expanded and after performing the desired reaming operation, cannot be retracted or collapsed and, therefore, it is impossible to remove the tool without the aid of fishing tools or other expensive operations.

It is an object of this invention to provide a simple, effective and reliable reamer for use in drilling with the rotary method.

It is a further object of my invention to provide a reamer of the character mentioned which is at all times under full control of the operator and will not expand to operating position until deliberately opened.

It is a further object of this invention to provide a reamer of the character mentioned which can be retracted or released from operating position at the will of the operator.

Another object and feature of my invention is to provide a reamer of the character mentioned in which the cutters are particularly large and effective.

It is a further object of my invention to provide a reamer of the character mentioned in which the general construction and formation of parts is simple, strong and durable.

A further object of my invention is to pro-

vide a reamer of the character mentioned which involves or includes no springs or other devices or constructions liable to fail or become inoperative.

A further object of this invention is to provide a reamer in which the cutters cannot be set in the expanded position until all of the cutters are in the expanded position.

There are many other noteworthy objects of my invention which, together with those above mentioned, will be best and more fully understood from the following detailed description of a typical form and application of the invention, throughout which description reference is had to the accompanying drawings, in which:

Fig. 1 is a side elevation of the reamer provided by this invention, showing it in combination with other standard drilling apparatus;

Fig. 2 is an enlarged vertical or longitudinal, detailed, sectional view of the tool provided by my invention;

Fig. 3 is a detailed, transverse, sectional view, taken as indicated by line 3-3 on Fig. 2.

Fig. 4 is a detailed, transverse, sectional view, taken as indicated by line 4-4 on Fig. 2;

Fig. 5 is a detailed, transverse, sectional view similar to Fig. 4, showing the parts in another operative position;

Fig. 6 is a detailed, transverse, sectional view, taken as indicated by line 6-6 on Fig. 2; and

Fig. 7 is a detailed, transverse, sectional view, taken as indicated by line 7-7 on Fig. 2.

The tool provided by this invention is intended primarily to be used in or with the rotary method of well drilling and is particularly useful for under-reaming or enlarging a bore. It is to be understood, however, that the invention is not limited to operation under any specific or particular conditions, nor is it necessarily limited to operation in a previously drilled hole. I will state, for example, that the tool may be incorporated in or used in combination with a drill of any

suitable construction to follow the drill and enlarge the hole or bore formed by it.

The preferred construction embodying my invention includes, generally, a body 10, an enlargement or head 11 on the lower portion 5 of the body, an enlargement or head 12 on the upper portion of the body, a plurality of cutters 13 carried by and between the heads 11 and 12, and various other features and details of construction, the formation and functions of which will be hereinafter described.

The body 10 is elongate in form and is preferably a unitary or integral member extending centrally throughout the entire 15 length of the tool. The body 10 operates, generally, as a mounting or carrier for the various other parts of the tool. In the particular arrangement or application of the invention shown in the drawings, the tool is connected in a string of drilling tools, that is, 20 between a drill pipe 14 and a bit 15. In a case of this kind, the upper end of the body 10 may be provided with a tapered, screw-threaded projection 16 to receive a coupling member 17 which operates to connect the drill pipe with the body. The lower end of the 25 body 10 may be provided with a screw-threaded part 18 which receives a coupling 19 provided with a screw-threaded socket 20 to receive the bit 15. In the drawings, I have shown a typical fishtail bit which may be run in advance of the reamer as a pilot.

The lower head 11, provided on the lower 30 end portion of the body 10, is rigid with the body and is provided as a carrier for the lower ends of the cutters. In the drawings, I have shown the head 11 formed separate from the body 10 and held on the body between a downwardly facing shoulder 22 and the upper end of the coupling member 19. 35 The head 11 may be fixed on the body 10 against rotation by any suitable means; for instance by means of a key 23. The head 11 is provided in its upper end with sockets or 40 openings 25 to receive the cutters. In practice, I prefer to provide bushings 26 in the openings 25 to take the wear of the cutters.

The upper head 12 is provided on the body 45 10 at a point spaced a substantial distance above the lower head 11 and includes, generally, two sections 28 and 29. The section 28, which is the uppermost section of the head, is rigid on the body 10 and may be considered a part of the body. The section 29 is 50 arranged below the section 28 and is mounted for rotation on the body. The section 28 is shown formed separate from the body 10 in which case it may be retained on the upper end of the body by the coupling member 17 55 and may be fixed against rotation on the body by means of a key 30, or the like.

In accordance with my invention, I provide means whereby the sections 28 and 29 of the upper head 12 are related or interconnected 60 so that the lower section 29 is allowed

a limited amount of rotation relative to the upper section 28. This means may constitute inter-meshing parts on the sections; for instance, the upper section 28 may be provided at its lower side with a plurality of 70 spaced lugs 31, while the lower section 29 may be provided on its upper side with a plurality of spaced lugs 32 which fit between the lugs 31 with sufficient clearance to allow the desired amount of relative rotation between 75 the sections. This particular form of interconnection is desirable as it is simple and at the same time very strong and durable. With this arrangement, rotative strain imparted to the upper section 28 through the key 30 is in 80 turn effectively imparted or communicated to the lower section 29 through the engagement of the lugs 31 with the lugs 32. It is desirable, in practice, that the inter-meshing lugs 31 and 32 be protected or housed so that mud 85 or foreign matter will not get between the lugs to prevent their functioning in the desired manner. To this end, I may provide an annular flange 33 on one of the sections, for instance, on the upper section to extend downwardly around the lugs and thus enclose them.

The lower section 29 of the upper head 12 carries a plurality of blocks 35 which hold the upper ends of the cutters 13. In accordance with my preferred construction, guideways 36 are formed in the lower side of the section 29 to slidably carry the blocks 35. The guideways 36 have parallel side walls and are disposed tangentially. There is, of course, one guideway for each cutter included in the tool and, in practice, the several guideways are equally spaced around the section 29 in the manner shown in the drawings. The particular angle or inclination of the guideways may be varied somewhat, depending upon the design, size and other like features entering into the tool, it being essential, generally, that the inclination or angularity be such as to obtain the action or mode of operation hereinafter described. The blocks 35, which hold the upper ends of the cutters 13, are slidable in the guideways between out positions where they are in the outermost parts of the guideways, as shown in Fig. 4 of 100 the drawings, and in positions where they extend into sockets or recesses 40 formed in the body 10. The blocks 35 are proportioned with reference to the guideways so that they are entirely within the guideways when out, 105 as shown in Fig. 4, thus allowing the body 10 to assume a position with reference to the section 29 where the recesses 40 are out of register with the guideways and the body engages inner ends of the blocks to positively 110 hold the blocks out. In practice, I provide parts or stops 42 which project into the guideways at their outer ends to stop or positively 115 limit the outward movement of the blocks. When the blocks 35 are out and the parts are 120

in operating position, as shown in Fig. 4, the stops 42 positively hold the blocks against outward movement while the body 10 positively holds the blocks against inward movement. The recesses 40 provided in the body 10 are proportioned to more or less freely receive the inner ends of the blocks.

The blocks 35 are provided with openings 50 to receive the upper ends of the cutters.

- 10 In a case where it is desired to get the maximum amount of expansion of the cutters, the openings 50 are located as close as possible to the outer ends of the blocks to thus carry the upper ends of the cutters far out when the blocks move out to the position shown in Fig. 4. It will be obvious from inspection of the drawings that the openings 50 may be made to more or less loosely receive the ends of the cutters so that parts do not bind due to the 20 change of angularity between the blocks and cutters in the operation of the device between the two positions. The openings 50 are in the form of sockets and, in practice, I may provide thrust washers 50a in the 25 openings, as shown in the drawings. It is also to be understood that the lower ends of the cutters are carried by the lower head so that they can operate freely between the in and out position. It is desirable, in practice, 30 to house or enclose the parts just described to prevent them with being clogged with mud or foreign matter and, therefore, I may provide a housing 60 around the section 29 to close the guideways. The housing is provided with openings 51 which allow free operation of the cutters.

- The cutters 13 used in carrying out my invention may vary considerably in design and construction, it being preferred in most cases 40 to use roller cutters such as are employed, generally, in rock drills, and the like. In the drawings, I have illustrated roller cutters and have shown the exteriors of the rollers occupied by sharp cutting parts or teeth 65. 45 In the construction shown in the drawings, the cutters are provided at their lower ends with trunnions 67 which are rotatively carried in the bushings 26 carried by the head 11 and are provided at their upper ends with 50 trunnions 68 which are carried in the openings 50 provided in the blocks 35.

- In accordance with my invention, I prefer to form the cutting teeth 65 in rows extending longitudinally of the cutters. The rows of 55 teeth are preferably pitched or spiralled somewhat around the cutters so that movement of the tool through a hole with the teeth of the cutters engaging the walls of the hole causes the cutters to tend to move the blocks 35 in the guideways. By pitching the rows of teeth 65 in one direction, the tendency will be for the blocks 35 to move outwardly in the guideways while by pitching the rows of teeth in the opposite direction, the tendency 60 will be for the blocks 35 to move inwardly in

the guideways. It is to be particularly noted that the rollers provided in my construction are comparatively large in diameter. In practice, I provide recesses 70 in the body between the heads 11 and 12 to receive the rollers. These recesses are clearly illustrated in Fig. 6 of the drawings. It is to be understood, of course, that an opening 71 is formed longitudinally through the body 10 so that mud-laden fluid, or the like, may be circulated through the tool.

The tool is adapted to be lowered into a well with the cutters in the in or collapsed position. When the cutters are in the in position, the blocks 35 project into the sockets 40 in the body. When the tool has been lowered to the point at which it is desired to start the reaming operation, it is rotated by rotating the drill pipe 14 in a right handed direction when viewed from above. When the cutters are in the in position and the tool is rotated, the rotative strain is imparted from the body 10 to the section 29 and cutters 13 through the blocks 35. This is because the co-operating lugs 31 and 32, which interconnect the sections 28 and 29, are not in driving engagement when the body 10 and section 29 are in position to allow the blocks 35 to extend into the sockets 40. The end walls 72 of the sockets 40 bear against the inner end portions of the blocks 35. It is to be noted that the walls 72 of the sockets are inclined or angularly disposed to be parallel with the guideways 36 when the parts are in the position shown in Fig. 5 and that this inclination of the walls 72 tends to force or urge the blocks outwardly in the guideways 36 as the blocks 35 are carried around with the body. This tendency for the cutters 13 to move outwardly in the guideways is aided by centrifugal force which acts on the cutters and blocks to throw them outwardly with the result that the cutters feed outwardly until they finally reach the expanded or out position, as shown in Figs. 2 and 4 of the drawings. Particular attention is called to the fact that the cutters will not feed out positively and quickly in a manner to become jammed or stuck in the wall of the hole, but on the other hand, may feed out slowly and operate to cut away or into the wall of the hole as they are being expanded so that they are free in the hole when they reach the expanded position. At any time during the expanding operation, the cutters can be forced in if they engage an obstruction or are being expanded in a hard formation in which they might otherwise become tightly set. In practice, the inclination or formation of the parts above described, together with the centrifugal force acting on the cutters to throw them outwardly, causes the cutters to effectively feed out to the expanded position. When all of the cutters have reached the expanded position, the blocks 35 are limited against further outward

105 110 115 120 125 130 135 140 145 150 155 160 165 170 175 180 185 190

movement by the stops 42. The moment all of the blocks 35 reach the out position, the body 10 is free to rotate relative to the section 29 so that it moves behind or under the inner ends of the blocks 35 and thus locks the blocks in the out position so that the tool can be forced or fed against its work without the cutters being forced inwardly or collapsed. The rotation, which takes place between the body 10 and section 29 to move the body behind the blocks to lock the cutters out, moves the lugs 31 into engagement with the lugs 32 so that the section 29 is driven directly from the section 28. Under this condition, the driving strain is imparted directly from the section 29 to the blocks 35 occupying the guideways in the section 29. It is to be noted that my arrangement and construction allows for comparatively large bearing surfaces between the section 29 and the blocks 35. With my construction and arrangement as above described, the movement of the blocks between the in and out positions swings or tilts the upper ends of the cutters circumferentially as well as radially. In practice, I may utilize this circumferential shifting of the cutters to aid the opening or expanding of the cutters or to aid the closing of the cutters. For instance, if the parts are designed and proportioned so that the upper ends of the cutters move circumferentially from an inclined position to an upright position in which they are inclined only in a radial direction, they will tend to feed out or expand as the tool is lowered in the hole, whereas, if this positioning is reversed, they will tend to collapse or move inwardly as the tool is lowered in the hole. The drawings show the latter arrangement with the collapsed cutter in a vertical plane radial of the tool center, the upper ends of each cutter being displaced behind that vertical radial plane when expanded. In Fig. 2 the collapsed position of a cutter, viewed face on, is indicated by the center line A; the expanded position by center line B. This pitching of the cutters, together with the pitching of the rows of teeth on the cutters, may be utilized to great advantage in assuring proper operation of the tool. On straight lowering, the upward drag of the wall (pipe or formation) on the cutters tends to straighten them up and thus keep them in collapsed position. Rotation, however, immediately throws the upper ends around to a position behind the vertical radial plane of the lower ends—that is, the upper ends, in addition to being tilted outwardly as shown in Fig. 2, are also tilted rearwardly with reference to the direction of rotation, as is indicated in Fig. 2. The effect thus is that the upper and most outwardly projecting end of the expanded cutter drags behind the lower end. When the desired reaming operation has been completed, the cutters can be collapsed or moved to the in position by ro-

tating the drill pipe 14 in the reverse direction (left-handedly) enough to bring the body 10 in position where the sockets therein will receive the ends of the blocks 35. When the body is in this position, it is apparent that the blocks are no longer locked out and, therefore, the cutters will readily collapse, allowing the tool to be withdrawn from the well.

Having described only a typical preferred form of my invention, I do not wish to limit myself to the specific details set forth, but wish to reserve to myself any changes or variations that may appear to those skilled in the art or fall within the scope of the following claims.

Having described my invention, I claim:

1. A tool of the character described including a body, a cutter having one end carried by the body, a block shiftable relative to the body and carrying the other end of the cutter, and a member rotatably carried on the body and carrying the block so that it is movable outwardly of the body, the block having a direct bearing engagement on the body.

2. A tool of the character described including a body, a cutter having one end carried by the body, a block carrying the other end of the cutter, and a member rotatably carried on the body and slidably carrying the block so that it is movable outwardly of the body, the block having bearing engagement with the body when in the out position.

3. A tool of the character described including a body, a cutter having one end carried by the body, a block carrying the other end of the cutter, a carrier for the block rotatable on the body and carrying the block so that it is movable to a position where the cutter is in an extended position, the body having a part to engage and hold the block in the extended position, and means whereby the carrier is engaged to rotate with the body when the said part of the body engages the block.

4. A tool of the character described including a body, a cutter having one end carried by the body, a block carrying the other end of the cutter, and a member mounted on the body and carrying the block so that it is movable to an out position where the cutter projects from the body, said member being rotatable on the body only when the cutter projects from the body so that a part of the body engages behind the block to hold it in the out position.

5. A tool of the character described including a body, a cutter having one end carried by the body, a block carrying the other end of the cutter, a carrier for the block rotatable on the body and carrying the block so that it is movable to a position where the cutter is in an extended position, the body having a part to engage and hold the block in the extended position, and means whereby the carrier is engaged to rotate with the body

when the said part of the body engages the block, said means including cooperating lugs on the carrier and in connection with the body.

6. A tool of the character described including a body, a cutter having one end carried by the body, a block carrying the other end of the cutter, a carrier for the block rotatable on the body and carrying the block so that it is movable to a position where the cutter is in an extended position, the body having a part to engage and hold the block in the extended position, and means connecting the body and carrier for limited relative movement and so that the carrier is rotated with the body when the said part of the body engages the block.

7. A tool of the character described including a body, a cutter having one end carried by the body, a block carrying the other end of the cutter, a carrier for the block rotatable on the body and carrying the block so that it is movable to a position where the cutter is in an extended position, the body having a part to engage and hold the block in the extended position, and co-operating lugs connecting the body and carrier for limited relative movement and so that the carrier is rotated with the body when the said part of the body engages the block.

8. A tool of the character described including a body, a cutter having one end carried by the body, a block carrying the other end of the cutter, and a member rotatably carried on the body and slidably carrying the block, the body having a recess to receive the block in the in position and having a part to engage behind and hold the block in the out position.

9. A tool of the character described including a body, a cutter having one end carried by the body, a block carrying the other end of the cutter, and a member rotatable on the body and having a guideway slidably carrying the block, the guideway extending tangentially relative to the body, the body having a recess to receive the block in an in position and having a part to engage behind the block to hold it in the out position, the recess and said part being movable into and out of operative position by relative rotation between the body and said member.

10. A tool of the character described including a body, a cutter having one end carried by the body, a block carrying the other end of the cutter, a member rotatable on the body and having a guideway slidably carrying the block, the guideway extending tangentially relative to the body, the body having a recess to receive the block in an in position and having a part to engage behind the block to hold it in the out position, the recess and said part being movable into and out of operative position by relative rotation between the body and said member, and

means whereby the said member is connected with the body to operate therewith when the said part of the body is engaged behind the block.

11. A tool of the character described including a body, a cutter having one end carried by the body, a block carrying the other end of the cutter, a member rotatable on the body and having a guideway slidably carrying the block, the guideway extending tangentially relative to the body, the body having a recess to receive the block in an in position and having a part to engage behind the block to hold it in the out position, the recess and said part being movable into and out of operative position by relative rotation between the body and said member, and co-operating lugs whereby the said member is connected with the body to operate therewith when the said part of the body is engaged behind the block.

12. A tool of the character described including a body, a cutter having one end carried by the body, a block carrying the other end of the cutter, a member rotatable on the body and having a guideway slidably carrying the block, the guideway extending tangentially relative to the body, the body having a recess to receive the block in an in position and having a part to engage behind the block to hold it in the out position, the recess and said part being movable into and out of operative position by relative rotation between the body and said member, and means for limiting outward movement of the block in the guideway.

13. A tool of the character described including a body, two heads spaced apart longitudinally on the body, and a roller cutter carried between the heads, one of the heads including a section fixed to the body, a section rotatable on the body to be driven from the first mentioned section, and a block slidably carried by the rotatable section and holding one end of the cutter.

14. A tool of the character described including a body, two heads spaced apart longitudinally on the body, and a roller cutter carried between the heads, one of the heads including a section fixed to the body, a section rotatable on the body, means connecting the section for limited relative rotary movement, and a block slidably carried in a tangential guideway in the rotatable section, the block holding one end of the cutter.

15. A tool of the character described including a body, heads spaced apart longitudinally on the body, a roller cutter carried between the heads, one of the heads having an opening to receive one end of the cutter, the other head including a section fixed to the body, a section rotatable on the body, co-operating lugs on the sections connecting the sections for limited relative rotary movement, a tangential guideway in the rotatable sec-

tion, and a block carrying the other end of the cutter and slidably carried in said guideway.

16. A tool of the character described including a body, two heads spaced apart longitudinally on the body, a roller cutter carried between the heads, one of the heads including a section fixed on the body, a section rotatable on the body, means connecting the sections for limited relative rotary movement, a tangentially disposed guideway in the rotatable section, and a block carrying one end of the roller and slidably carried in the guideway, the body having a recess to receive the block in the in position and having a part to engage behind the block in the out position.

17. A tool of the character described including an elongate body, two spaced heads on the body, and a plurality of roller cutters carried by the heads, the body being recessed between the heads to receive the cutters, one of the heads including two sections, one fixed to the body, the other rotatable on the body, means connecting the sections for limited relative rotary movement, the rotatable section having a plurality of tangentially disposed guideways, and blocks holding the ends of the cutters slidably carried in the guideways, the blocks being slidable between in positions where they project into recesses in the body and out positions where the rotatable section can rotate on the body so that parts of the body engage behind the blocks.

18. A tool of the character described including, a body, a cutter having its lower end connected with the body for tilting motion, a block movable relative to the body and carrying the other end of the cutter, and means whereby the block shifts in a plane substantially tangential of the body.

19. A tool of the character described including, an elongate body, a cutter having one end rotatably carried by the body, a block shiftable laterally of the body and carrying the other end of the cutter, and a member rotatably carried by the body and carrying the block to shift it relative to the body.

20. A tool of the character described including, a body, a roller cutter having one end rotatably carried by the body, a block shiftable relative to the body and carrying the other end of the cutter, and a member rotatable on the body having a tangential guideway slidably carrying the block, the body having a recess to receive the block in an in position, and means whereby the block is shiftable to an out position only on relative movement between the body and said member, the body having a part to engage behind the block to hold it in an out position.

21. In an expansive reaming tool, a vertically elongate body rotatable about a central vertical axis, a cutter carrying mandrel pin

extending vertically of the body and having its lower end mounted in the body for tilting motion, a cutter mounted on the mandrel pin, and means in the upper part of the body guiding the upper end of the mandrel pin in movement in a plane nonradial of the body. 70

22. In an expansive reaming tool, a vertically elongate body rotatable about a central vertical axis, a cutter carrying mandrel pin extending vertically of the body and having its lower end mounted in the body for tilting motion, a cutter mounted on the mandrel pin, and means in the upper part of the body guiding the upper end of the mandrel pin in movement substantially tangential of the body. 75

23. In an expansive reaming tool, a vertically elongate body rotatable about a central vertical axis, a vertically extending mandrel pin, a rotatable roller cutter surrounding the mandrel pin, the mandrel pin projecting above and below the upper and lower ends respectively of the roller cutter, means mounting the lower end of the mandrel pin on the body for swinging movement of the mandrel pin about its lower end as a center, the upper part of the body having a slot in a plane substantially tangential to the body, the upper end of the mandrel pin entering and being guided by said slot. 80

24. In an expansive reaming tool, a vertically elongate body rotatable about a central vertical axis, and a longitudinally extending cutter mounted on the body and movable between a collapsed position wherein the cutter lies substantially in a vertical plane radial of the body center and an expanded position wherein one end of the cutter lies radially outwardly of the other end and also lies circumferentially behind said other end 100 with reference to the direction of rotation.

25. In an expansive reaming tool, a vertically elongate body rotatable about a central vertical axis, a longitudinally extending roller cutter mounted on the body and normally standing in a collapsed position substantially in a vertical plane radial of the body center, and means for guiding the upper end of the cutter from the collapsed position to an expanded position wherein that end lies radially outwardly of the other end and also lies circumferentially behind said other end with reference to the direction of rotation. 110

26. In a reamer, a vertically elongate body rotatable about a central axis, and an elongate roller cutter mounted on the body and extending, in its cutting position, diagonally upwardly and outwardly and circumferentially with respect to the body axis, so that the upper end of the cutter lies outward of and circumferentially displaced from the lower end. 120

27. In a reamer, a vertically elongate body rotatable about a central axis, and an elongate roller cutter mounted on the body and ex- 125

tending, in its cutting position, diagonally upwardly and outwardly with respect to the body axis and also diagonally with respect to a plane radial of the body axis.

5 28. In a reamer, a vertically elongate body rotatable about a central axis, and an elongate roller cutter mounted on the body and extending, in its cutting position, diagonally upwardly and outwardly with respect to the body axis and also diagonally with respect to a plane radial of the body axis, so that its upper and outermost end lies circumferentially behind the lower end with reference to the direction of rotation.

10 15 In witness that I claim the foregoing I have hereunto subscribed my name this 3rd day of February, 1927.

LELAND S. HAMER.
